DRIVE PAWL FOR ELECTRICALLY WOUND
CLOCKS

Roland Siefert, Schwenningen (Neckar), Germany, assignor to Kienzle Uhrenfabriken A.G., Schwenningen (Neckar), Germany

Filed June 27, 1962, Ser. No. 205,579

6 Claims. (Cl. 74—577)

This invention relates to a drive pawl for electromagnetic wind-up devices for clocks or other time pieces. The drive pawl and associated ratchet wheel provide the working connection between a source of mechanical energy, such as a spring periodically stressed by a clapper armature, and the running works of the time piece. The hitherto usual drive pawls are often biased with a helical torsion spring to improve engagement with the ratchet wheel. If such a spring be strong in order to prevent a jumping out from the associated toothed there is the disadvantage during retraction, or backward motion when the pawl rides without action on the ratchet wheel, that the friction is very high. This leads to wide variations in winding torque, frequency of winding and consequent torque on the works. In order to reduce friction, weak springs are frequently used but they have the characteristic of rather often allowing the pawl to spring out of working position and consequently the time piece is thrown out of time or put out of order.

Moreover simple leaf springs have been employed but they, too, also either press too strongly so that the torque required for wind-up when the pawl rides backward over the teeth becomes large or the leaf springs must be long and so lack lateral stability.

The construction of a drive pawl according to the present invention avoids the above mentioned disadvantages. The pawl itself is a resilient arm, and so the need for a helical or coil spring is eliminated which is advantageous both as to operation and to production costs.

In the accompanying drawing showing, by way of example, two of many possible embodiments of the invention,

FIG. 1 is a perspective of a winding device with parts of a clockworks;

FIG. 2 is a plan of a drive pawl according to the invention;

FIG. 3 is a vertical sectional view of the pawl, the section being taken substantially along the line 3—3 of FIG. 2 looking in the direction of the arrows of said line;

FIG. 4 is a plan of another form of the pawl, and

FIG. 5 is a vertical sectional view of the pawl of FIG. 4 the section being taken along the line 5—5 of FIG. 4, looking in the direction of the arrows of said line.

The operation of a wind-up device can be readily understood by reference to FIG. 1. An electromagnet 10 periodically attracts a clapper armature 11 which strikes an eccentric cylindrical pin or crank 12 mounted on an oscillatory disc 13 of appreciable mass. The disc is mounted on a works plate 14 for oscillation about a stub shaft 15 so that the armature slings or turns the disc when the crank is struck. When the disc turns clockwise as shown in the drawing it stretches a tension spring 16 attached to the plate 14 and an eccentric portion of the disc. At the same time the drive pawl, generally designated 17, on the crank 12 rides backward over the ratchet wheel 18 fast on a works shaft 19. In practice, a stop pawl (not shown) is often used to prevent any backward turning of the wheel, though in some constructions this is not necessary especially if the friction of the drive pawl is kept low. When the disc reaches its limit of turning, against the tension of the spring, the drive pawl then engages the ratchet wheel so that the spring may, through

2

the pawl, drive the wheel 18 and work shaft 19 of the clockworks.

The pawl 17 is of springy strip metal having an engagement down-turned lip portion 20 at one end near a yoke portion 21 from which extend, in a generally opposite direction, two wide outer parallel arms 22 and a narrower tongue 23 between. The outer end portions 24 of the arms are each cylindrically curved to embrace, side by side and coaxially, slightly more than half the circumference of the crank pin 12.

The tongue 23, between the arms and spaced laterally therefrom, is resiliently bent from the plane of the arms and resiliently engages the crank pin on the opposite side of the axis of pin from the major portion of the curved ends so as to provide a retaining force to increase the holding of the ends around the cylindrical pin. The pawl is secured against undue movement of the curved ends 24 in the direction of the axis of the pin 12 by the provision of a minor chordal slot 25 in the pin in which the tongue 23 is disposed. The tongue prevents the undue movement by engagement against one or the other of slot side walls 27 and bears resiliently against the inner edge 26 of the slot to prevent an undesired flapping of the pawl or to provide bias to hold the lip 20 in the teeth of the ratchet wheel 18.

The pin 12 oscillates about the axis of the stub shaft 15. If the pin 12 is fast on the disc, as it preferably is, the slot edge 26 turns about the stub shaft, and during oscillation of the disc, the edge 26, if the stub shaft 15 and the works shaft 19 are coaxial, remains the same distance from the periphery of the ratchet wheel 18, and the spring bias on the pawl remains constant.

However, the stub and works shafts need not be exactly coaxial and so the tension on the pawl may be made to vary according to the position of the disc, which will also affect the bias of the pawl due to gravity. Thus according to the combination of spring tension and weight the pawl may have as desired a nearly constant, as well as a distorted, bias against the ratchet wheel depending on the positions of the disc and of the axis of the said shafts. Depending on the height and slope of the ratchet wheel teeth it may be desirable to have the pawl bias against the wheel stronger, say, when the disc approaches run-down position.

By a system of gears (not shown), the pin 12 may turn relative to the disc, as the latter turns about the stub shaft, and so vary the spring tension on the pawl according to the position of the disc.

In another form of the pawl as shown as 17a in FIGS. 4 and 5 the arms 22 of FIGS. 3 and 4 are replaced by side flanges 22a at right angles to the plane of the yoke portion 21. The outer end portions of the flanges are provided with aligned bearing holes 28 receiving the pin 12. In this form of the invention the tongue disposed in the slot overlies the pin and is on the outer edge 26a of the slot to cause the pawl to bear against the ratchet wheel. The pawl 17a may be made quite rugged by the provision of a diamond shaped dimple 29 at the line of junction between the lip and yoke portion and by a web-like tie piece 30 between the side flanges.

In either form of the invention the tongue may be sprung temporarily to permit the sliding of the pawl onto the pin 12 longitudinal thereof to register the tongue and slot, and then the tongue is allowed to engage the appropriate edge of the slot in order to cause the pawl to bear against the ratchet wheel. The slot walls prevent the tongue and pawl as a whole from unduly moving laterally.

The invention claimed is:

1. A drive pawl combination for an oscillatory windup device of an electromagnetically wound time piece, characterized by the inclusion of an oscillatory inertia mem-

ber, a crank pin on the member, said pin having a chordal slot therein, a pawl mounted on the pin for turning slightly thereon and having a resilient tongue in the slot for tending to turn the pawl about the pin, the tongue being engageable with the side walls of the slot to limit lateral movement of the pawl, and a ratchet wheel engageable with the pawl.

2. In an electrically wound clock, an inertia member mounted for turning and a cylindrical crank pin thereon, the pin having a chordal slot therein, an elongated pawl having a yoke and lip portion at one end portion for engagement with a ratchet wheel and substantially mono-planar arms terminating at the other end as slightly more than semicylindrical claws partially embracing the pin on each side of the slot as bearings for the pawl, a resilient tongue fast on the yoke portion and in the slot and tensed against an edge of the slot parallel with the axis of the pin for tending to turn the pawl and claws about the pin, said tongue being adapted to engage the side walls of the slot to prevent lateral movement of the pawl on the pin, and a ratchet wheel for the pawl to engage on.

3. In an electrically wound clock, an inertia member mounted for turning and a cylindrical crank pin thereon,

the pin having a chordal slot therein, two like substantially parallel arms of strip material each having aligned bearing openings at one of their end portions and receiving the pin, a yoke portion connecting the two arms at their other end portion, and a lip portion adapted to engage a ratchet wheel and integral with the yoke portion, a resilient tongue fast on the yoke portion and between the arms and tensed against the pin and lying in the slot, for tending to turn the arms about the pin and limiting motion of the arms in a direction axially along the slot.

4. In a clock as claimed in claim 3 said tongue bearing on an edge of the slot parallel with the axis of the pin.

5. In a clock as claimed in claim 4, said arms lying in substantially a single plane to which the axis of the pin is parallel.

6. In a clock as claimed in claim 4 said arms lying in different planes to which the axis of the pin is substantially perpendicular.
